W. W. McMAHAN.

APPARATUS FOR COMPRESSING CARBON BLACK AND OTHER PULVERULENT MATERIALS.

APPLICATION FILED JUNE 18, 1919.

1,372,181.

Patented Mar. 22, 1921.

Inventor,

William W. McMaham,

By his Attorney.

Bruce Stevenson

UNITED STATES PATENT OFFICE.

WILLIAM W. McMAHAN, OF DETROIT, MICHIGAN, ASSIGNOR TO MORGAN & WRIGHT,
A CORPORATION OF MICHIGAN.

APPARATUS FOR COMPRESSING CARBON-BLACK AND OTHER PULVERULENT MATERIALS.

1,372,181.

Specification of Letters Patent. Patented Mar. 22, 1921.

Application filed June 18, 1919. Serial No. 305,156.

To all whom it may concern:

Be it known that I, WILLIAM W. McMAHAN, a citizen of the United States, residing at Detroit, county of Wayne, and State of Michigan, have invented certain new and useful Improvements in Apparatus for Compressing Carbon-Black and other Pulverulent Materials, of which the following is a full, clear, and exact description.

10 This invention relates to apparatus for compressing pulverulent material and especially flocculent materials such as carbon black, and it has for its object the provision of means for changing the physical state of the said carbon black or similar material from a loose powder, comprising particles isolated from each other by air, to a solid cake in which the particles are firmly held together by molecular cohesion.

20 Heretofore it has been found difficult to compress carbon black into permanent cake form. I have discovered that this difficulty may be overcome by so designing the compressing apparatus as to permit the air contained within the mass of the powder to escape freely during the compressing operation.

25 This case is a continuation in part of my application Serial No. 129,290, filed November 3, 1916.

The invention will be understood by reference to the accompanying drawing which illustrates an embodiment of the invention designed to compress the powder into a cylindrical solid cake.

The figure of the drawing is a longitudinal sectional view of the said apparatus.

The embodiment of the apparatus illustrated in the drawing consists of a base A, formed with a central aperture 1 enlarged toward its lower end to form a fluid chamber 2. Within the aperture 1 of the base member A and projecting within chamber 2 is a ram 3. The base member A at its upper end is provided with the flange or flanges 4, formed with apertures 5 to receive the reduced lower ends of stud bolts 6, the reduced upper ends 6^x of said bolts being fitted within apertures 7 in the lower flange of a press head B, the latter having formed therein a compression chamber 8 in register with the ram 3. The base and head

members of the press are held together in fixed relationship by means of the studs 6 and nuts 9 on the threaded ends of the studs. 55

The compression chamber 8 may be opened and closed by means of a cap member 10, the latter being pivotally mounted at 11 upon a bracket extension 12 of the press head B, the cap being held in closed position by means of a latch member 13.

A duct is formed in the wall of chamber 2, and a pipe 14 is threaded within said duct so that fluid under pressure may be forced into chamber 2 to operate the ram 3, and a suitable exhaust duct 14^x may be provided for the said chamber. A packing 15 may be disposed intermediate the ram and the base member A, and means such as ring 16 and screws 17 may be provided for compressing the packing about the ram. 65

The cap member 10 of the press is formed with one or a series of apertures 18 for a purpose to be described.

In operation, the carbon black or other pulverulent material will be placed within the compression chamber 8; and a screen 19 is preferably employed intermediate the said material and the cap member 10. The cap member is then locked in position and pressure is applied to the lower end of the ram, the pulverulent material thus being compressed within the compression chamber into the form of a solid cake. During the upward movement of the ram the air is forced from between the particles of the material and is dispersed into the atmosphere through the screen and vents 18. 75

It will be understood that the vent opening or openings may be formed either in the cap member 10 or at other points of the compression chamber, such as through the side wall of the latter; and the screen may be formed of porous paper, cloth, metal or other suitable material. When the compressing operation has been completed the compression chamber may be opened and a further upward movement of the ram may be employed to force the cake of powder out of the chamber. 85

If desired, the carbon black or other material may be inclosed in an envelop such as a paper or cloth bag at the time it is placed in the compression chamber. In such case 95

the bag may serve as a screen to prevent the forcing out of the powder through the vent openings.

Having thus described my invention, what I claim and desire to protect by Letters Patent is:

1. In apparatus of the character described, a compression chamber, a ram disposed within the compression chamber, a closure for the compression chamber at that end of the latter opposite the ram, said closure comprising a hinged cap and locking means for the cap, and means for imparting a compression stroke to the ram in the direction of the said cap.
2. In apparatus of the character described, a compression chamber, a ram disposed within the compression chamber and means for imparting an endwise movement thereto, a closure for the compression chamber at that end of the latter opposite the ram, said closure comprising a hinged cap and locking means for the cap, the said cap being formed with a vent

opening for the passage of air from the 25 chamber to the atmosphere.

3. In a compression apparatus, the combination of a compression chamber, a hydraulic ram disposed therein, a closure for the chamber and locking means therefor, air 30 vents in the closure, screens intermediate the vents and chamber, and fluid means for actuating the ram.

4. In apparatus of the character described, a base member formed with a fluid 35 chamber, a ram supported in said base member and in register with the fluid chamber, a press head rigidly secured to the base member above the latter and formed with a compression chamber in register with the 40 upper end of said ram, the ram forming a bottom wall for the compression chamber, a hinged cap for the compression chamber, and locking means for the cap.

Signed at Detroit, Michigan, this 11th day 45 of June, 1919.

WILLIAM W. McMAHAN.
